THREAD REMOVER FOR WEFT
REPLENISHING LOOMS

Benjamin W. Brouwer, Auburn, and John T. Kennedy, Worcester, Mass., assignors to Crompton & Knowles Loom Works, Worcester, Mass., a corporation of Massachusetts

Application March 8, 1950, Serial No. 148,386

22 Claims. (Cl. 139—256)

1

This invention relates to improvements in thread removing mechanism for weft replenishing looms and it is the general object of the invention to provide a pneumatic remover for the thread of the outgoing bobbin so constructed as to control the thread more positively than has been possible in previous removers of this type.

Pneumatic thread removers now in use generally move the thread intake mouth to a position behind the thread of the outgoing bobbin during the latter part of the down motion of the trans-ferrer arm as the lay approaches front center, and backward motion of the lay is relied upon to move the thread to the mouth. If the intake mouth is slightly above its correct pick-up position it will fail to attract and remove the thread. Such removers when rising to their normal position do not exert any appreciable mechanical force on the thread tending to move it toward the intake mouth. Furthermore, in previous removers the intake mouth has been at the bottom of the tube of the remover when the latter is in normal position, and the thread has had a tendency to fall out of the mouth.

It is an important object of the present invention to provide a pneumatic thread remover mounted to move from a generally horizontal thread pick-up position toward a normal vertical position in which the intake mouth is at the upper end of the remover tube. In moving back to its normal position the remover acts mechanically and positively to lift the thread to a position where it will tend by gravity to fall toward the intake mouth.

The usual thread remover is employed in association with a form of thread cutter which severs the thread of the outgoing bobbin at a point close to the shuttle delivery eye rather late in the forward advance of the lay but generally prior to arrival of the ordinary thread remover at its pick-up position, thereby permitting the thread due to its resilience to snap away from the intake mouth. It is another object of the present invention to provide a thread remover which is moved to its thread pick-up position prior to the thread cutting operation so that the remover will be in position to attract the thread as soon as it is cut. The remover then returns to its normal position and positively lifts the thread before the replenished shuttle is picked, the return occurring generally when the magazine is reset at front center.

Weft replenishing looms of the multicolor type ordinarily employ a stationary magazine including a top or preventer shaft connected to some

2

form of shuttle position detector or feeler. A form of feeler which has been used in such mechanisms is pivoted to the magazine above and behind the lay and extends forwardly to be lowered from its normal raised position to shuttle detecting position when the magazine is set for transfer. This shuttle feeler overhangs the shuttle path when in detecting position and is generally formed with a downwardly and curved surface. It is a further object of the invention to provide a form of pneumatic thread remover having a guide to cooperate with the shuttle position detector when the latter is in detecting position so that during forward motion of the lay a thread engaging the under side of the shuttle feeler will be directed by it toward the intake mouth of the remover.

When the thread of the outgoing bobbin is cut near the shuttle eye and is picked up by a thread remover at a point between its ends a double strand or loop of the thread is drawn into the thread remover. Some yarns are prepared for weaving by the application thereto of a size or the like to strengthen and stiffen the thread, but because of the size the thread offers some resistance to bending or the formation of the aforesaid loop. Thread removers as heretofore constructed have generally been made of tubes circular in cross section, although some of them are provided with an elongated intake mouth. It is a further object of the invention to make the thread remover with a tube which is flattened throughout its length so as to accommodate a larger bend in the thread without increasing the volume of air within the tube. The latter preferably has a cross section for the greater part of its length which is preferably the same as that of the intake mouth.

With these and other objects in view which will appear as the description proceeds, the invention resides in the combination and arrangement of parts hereinafter described and set forth.

In the accompanying drawings, wherein a convenient embodiment of the invention is set forth, Fig. 1 is a side elevation looking from the center of a loom of a multicolor weft replenishing mechanism having the invention applied thereto, the lay being shown in section and on front center and the thread remover being shown in normal non-pick-up position.

Fig. 2 is a front elevation looking in the direction of arrow 2, Fig. 1, showing the parts in normal position.

Fig. 3 is an enlarged vertical section on line 3—3, Fig. 2, showing the thread remover in nor-

inal non-pick-up position in full lines and in thread pick-up position in dotted lines,

Fig. 4 is a front elevation looking in the direction of arrow 4, Fig. 3, showing the parts in normal position,

Figs. 5 and 6 are detailed enlarged longitudinal sections on lines 5—5 and 6—6, respectively, Fig. 4,

Fig. 7 is an enlarged horizontal longitudinal section on line 7—7, Fig. 4,

Fig. 8 is a detailed vertical section on line 8—8, Fig. 6,

Fig. 9 is a diagrammatic view showing the shuttle position detector in detecting position and indicating the manner in which the thread remover moves if a transfer is revoked,

Fig. 10 is a diagrammatic side elevation showing the shuttle position feeler in down or detecting position and showing the thread remover in its thread pick-up position,

Fig. 11 is a diagrammatic plan view showing the thread to be removed extending from the thread cutter near the shuttle eye to the cloth and across the intake mouth of the remover, and

Fig. 12 is an enlarged detail cross section on line 12—12, Fig. 4.

Referring particularly to Figs. 1 and 2, the loom frame 10 supports a magazine M of the multicolor type having a transerrer arm 11 pivoted as at 12 and provided with a latch 13 normally in down position as shown in Fig. 1 but raised preparatory to a weft replenishing operation when the magazine is set for transfer. Rockably mounted in the upper part of the magazine is a preventer shaft 15 to the rear end of which is operatively attached a depending rod 16 connected to a shuttle position detector or feeler 17 pivotally mounted as at 18 to the magazine frame at a point above and rearward of the lay L when the latter is on front center. The feeler 17 extends in a generally horizontal forward direction over the lay and has a downwardly and forwardly curved under surface or edge 19 the forward end of which is upturned as at 20. The forward end of the preventer shaft 15 is connected to a second depending rod 21 operatively connected as at 22 to the latch 13.

The magazine is provided with bobbin delivery cradles the operating pins of which are shown at 24 for cooperation with the lower ends of vertical slides or bobbin releasers 25. These releasers have top and bottom lugs 26 and 27, respectively, for engagement with a color slide mechanism 28. The latter shifts horizontally under control of means moving in time relation with the shifting shuttle boxes at the opposite end of the loom (not shown herein) so that the color slide will register with the releaser 25 corresponding to the active shuttle.

An elongated arm or shelf 30 to prevent transfer is secured to the shaft 15 and will be under the dog 31 at the upper end of any releaser 25 which may be in raised position as a result of an upward motion of the releaser by the color slide 28 while the preventer shaft remains in normal position. When the color slide rocks clockwise, Fig. 2, and is in register with a previously raised releaser, the shelf 30 will be engaged by the dog corresponding to the raised releaser and as the latter descends the shaft 15 will turn in a clockwise direction, Fig. 2, from its normal position to its setting position, thereby causing downward movement of both of the rods 16 and 21, one effect of which is to move the shuttle feeler 17 downwardly to the position shown diagrammatically in Fig. 10 to shuttle feel-

ing position and another effect of which is to lift the latch 13 into transfer position. This operation sets the magazine for transfer and occurs while the lay L is in a position near back center. The descending releaser effects movement of a reserve bobbin to the transfer position indicated at B, Fig. 1.

If the shuttle is properly placed to receive a bobbin from the magazine the transfer will proceed in normal order and as the lay approaches its front center position the transerrer arm will effect bobbin transfer in shuttle S and the box back 35 on the lay will engage the surface 19 and lift the shuttle feeler and thereby restore the shaft 15 to its normal position and reset the magazine when the lay reaches front center. The resetting of the magazine and the exchange of bobbins in the shuttle is completed when the lay reaches front center.

The shuttle S has a thread delivery eye 36 to the left of which is a thread cutting flat plate 37 mounted on the shuttle for cooperation with a cutter 38 mounted on a lever 39. The latter is pivoted on a stud 40 and a spring 41 tends to move the cutter rearwardly for cooperation with the plate 37 to cut the thread T.

An arm 42 on lever 39 extends to the left of the stud 40, Fig. 2, and cooperates with a lug 43 on the transerrer arm 11. This lug normally holds the cutter 38 in forward position, but at the time of transfer the lug 43 moves forwardly, or to the right as viewed in Fig. 1, and permits spring 41 to move the cutter 38 rearwardly against the plate 37 to cut thread T. The thread cutting mechanism is somewhat similar to that heretofore used except that it is made in such manner as to insure cutting of the thread before the shuttle feeler is engaged by box back 35. The cutting operation occurs after the magazine is set for transfer and before bobbin transfer is completed.

Except as noted the matter thus far described is of common construction and operates in the usual manner, the cutter however operating earlier than has been customary heretofore.

In carrying the present invention into effect the magazine has secured thereto a support 50 the rear end of which carries a spring cup 51 receiving the rear end of a compression spring 52. A stud 53 fixed to the support 50 has pivotally mounted thereon a carrier 54 the upper part of which is provided with a spring cup 55 receiving the front end of spring 52. A bolt 56 extends through the spring cups 51 and 55 and has an adjusting screw 57 at the rear end thereof. Normally the spring is expanded with the cup 55 in its right hand position as viewed in Fig. 1, this position being determined by engagement of the nut 57 with cup 51 and the head of the bolt with cup 55. The spring permits rearward motion of the cup 55 and counter-clockwise movement of carrier 54 around stud 53, Fig. 1.

A support rod 60 secured as at 61 to the carrier 54 depends from the latter and has fastened to the lower end thereof a head or support 62 in which a tube 63 is secured by a set screw 64, see Figs. 6-8. The tube 63 has the right end thereof closed and serves as a bearing for a remover carrier 65 pivotally mounted thereon. Tube 63 is provided with a flange or shoulder 66 to position the carrier 65, and its left end, Fig. 7, is connected to a hose 67 in which subatmos-

pheric pressures exist or are created as described hereinafter.

Secured to head or carrier 65 is a thread remover tube 68 the interior 69 of which communicates with an air passage 70 in head 65 leading to tube 63. The latter has a port 71 located at its rear side, to the left as viewed in Fig. 3, and the air passage 70 is normally above the tube with all but a small part of it out of register with the port 71.

The tube 68 is part of a pneumatic remover designated generally herein at R and has a flat plate 72 secured thereto. This plate has an inclined edge 73 which leads to an intake mouth 74 at the end of tube 68 remote from carriage 65. A plate or member 75 also fixed with respect to the tube 68 has a thread engaging or lifting surface 76 extending more or less in the direction of the axis of tube 68 and away from carrier 65 and beyond mouth 74.

The carrier 65 is provided with an arm 77 pivoted as at 78 to an upwardly extending rod designated generally at 79. The upper end of rod 79 is connected as at 80 to an arm 81 secured to the preventer shaft 15. The lay L is provided with a transverse slot 82 to receive the plate 75 of the remover R. This slot extends below the path of travel of the shuttle, and the thread T of the outgoing bobbin at the time of transfer will extend above the slot.

Under normal conditions the parts will be in the position shown in full lines in Figs. 1 to 4, that is, with the remover in substantially vertical position so that a thread notch 83 defined between the edge 73 and plate 75 opens upwardly and leads downwardly to the intake mouth 74. Under these conditions the preventer shaft 15 will be in its normal position.

When the magazine is set for transfer the shaft 15 will rock as already described while the lay is in a position considerably rearward of front center and rod 79 will be raised and turn the head 65 counter-clockwise, Fig. 3, to move tube 68 to a horizontal position, or to the pick-up position indicated in dotted lines in Fig. 3. This turning of head 65 will place the plate 75 in register with the slot 82. When in this position the edge 73 of plate 72 will extend upwardly to a position above and forward of the adjacent part of surface 19 on the shuttle feeler 17, as indicated in Fig. 10, the shuttle feeler being down as a result of setting of the magazine for transfer and the notch 83 will open rearwardly, see Fig. 10.

When the remover moves to its pick-up position the air passage 70 registers fully with the port 71 and air will move into the intake mouth 74 due to the subatmospheric pressures in hose 67 existing at this time, or shortly thereafter.

As the lay advances the plate 75 will enter the slot 82 and the surface 76 will pass under the thread T. The thread at this time will be rearward of the plate 72 and below the surface 19 of the shuttle feeler 17, and during continued forward motion of the lay the thread will enter notch 83 and be directed to the intake mouth 74. If, during the forward movement of the lay, the thread should happen to be in high position it will be deflected downwardly by surface 19 of the shuttle feeler and guided by it into the notch 83.

As the transerrer arm descends the cutter 39 will sever the thread T into two parts one of which leads to the right from the cutter, Fig. 2, to be drawn back through the shuttle eye 36 by the outgoing depleted bobbin B1, see Fig. 11. The

other or second part of the thread extends to the thread remover and thence to the selvage of the cloth. This cutting operation occurs after the thread remover is in its pick-up position and preferably when the thread is moving toward or is at the intake mouth 74. As soon as the thread reaches the mouth subatmospheric pressures will draw the second part of the thread into the tube 68 and through the passages 70 and 71 into tube 63. Hose 67 is connected to a thread collector (not shown) of known form and into which the second part of thread T ultimately passes.

As the magazine is reset incident to upward movement of the shuttle feeler 17 by box back 35 as the lay approaches front center on its forward stroke the preventer shaft 15 will be restored to its normal position and in doing so will depress rod 19, thereby swinging the remover R from the dotted line position to the full line position shown in Fig. 3 to lift the thread T mechanically by a force exerted by the plate 75 and move the thread forwardly as well as upwardly. When the remover R assumes its upright or non-pick-up position notch 83 will open upwardly with the intake mouth at the upper end of tube 68, and the thread will be acted upon by gravity to fall along plate 75 and assume a position near, or across, intake mouth 74 if the thread has not already entered tube 68.

Occasionally the shuttle will fail to be completely boxed on the beat during which it is intended to be replenished, in which event it is necessary to prevent or revoke transfer to avoid a faulty operation. It is for this reason that the shuttle feeler 17 is employed. If the shuttle should be widely misplaced as suggested in Fig. 9 so that its front advancing upper edge engages the under surface 19 of the feeler 17 the preventer shaft 15 will be rocked and rod 79 will be depressed to restore the remover R to its normal position earlier than usual. In order that the remover may rise under these conditions without interference with the shuttle it is desirable that its rear end terminate at a point sufficiently in advance of the misplaced shuttle to permit it to swing upwardly and clear the shuttle as the lay continues to move forwardly.

If the shuttle should not be as widely misplaced as suggested in Fig. 9 but be only slightly misplaced, the shuttle feeler will start up a little later in the forward beat of the lay, but the remover will still be forward of the tapered part of the shuttle registering with it and will clear such tapering part when returning to normal position.

It may happen that the plate 75 will lift the thread at the time of revocation of transfer, in which event the uncut thread will be whipped against the plate when the shuttle is picked. In order to enable the thread to clear the remover under such conditions the edge 84 of the plate 75 toward the shuttle, the right edge as seen in Fig. 4, is curved or inclined in a direction toward the cloth so that even though the thread should enter notch 83 it will slide up along the thread clearing edge 84 and free itself as the shuttle is picked.

In order to make provision for possible interference between the shuttle and remover at the time of revocation the rod 79 is made with a yielding resilient member 85 shown in Fig. 1. This member includes an elongated element 86 somewhat in the form of a turnbuckle and having top and bottom heads 87 and 88, respectively. The lower part 89 of rod 79 extends upwardly through head 88 and has secured thereto a collar

90 resting on top of the lower head. Similarly, the upper part 91 of rod 79 extends downwardly through top head 81 and has a collar 92 secured to it under head 87. A compression spring 93 between the collars normally keeps the rod parts 89 and 91 spaced to give rod 79 its full or greatest length. The spring will compress to permit down motion of rod part 91 when the magazine is reset without necessarily requiring lifting of the remover R to its normal position if the shuttle by any circumstance should extend over the rear part of the remover. As soon as the lay moves rearwardly far enough to free the remover from the shuttle the spring 93 will expand and return the remover to its normal idle or non-pick-up position. In this connection it may be noted that if the shuttle should happen to exert a forward thrust on the remover when the latter is in its pick-up position the spring 52 will yield to permit the remover assembly to move forwardly. Rod 79 acts positively when being raised to set the remover for operation, but acts yieldingly when being depressed to return the remover to normal position.

By referring to Figs. 1 and 3 it will be seen that the axis around which the remover R turns is close to the front center position of the lay, and approximately in horizontal alignment with the top of the race plate 94 of the lay along which the shuttle travels. This relationship facilitates movement of the thread by the remover when the latter returns to its normal position and enables the thread to be lifted a minimum distance when being moved forwardly by the plate 75.

Fig. 11 illustrates diagrammatically the advantage of having the tube 68 flattened throughout the greater part of its length. At the instant of cutting or shortly thereafter the thread T will extend across the intake mouth 74. If the thread should be of the kind which is fortified with a sizing it may be sufficiently stiff to resist ready bending under pneumatic attraction resulting from subatmospheric pressures existing in tube 68 and exerted in the direction of arrow a, Fig. 11. By having the tube 68 flattened on its top and bottom as indicated in Fig. 12 a considerable width of the mouth 74 is attained lengthwise of the thread without a corresponding height. The wide mouth permits ready entrance of a large curve or bend in the thread, as indicated at b. The tube 68 is preferably of the same cross section as the mouth for the greater part of its length extending from the mouth to the carrier 65, resulting in a uniform flow of air within the tube, the volume of air however being kept to a minimum for efficient operation due to the shape of the tube.

In order that the thread extending from tube 68 into tube 63 may be under some pneumatic action when the remover R is reset to its normal position the air passage 70 and port 71 will be as shown in Fig. 6, that is, the port is not completely closed but allows a slight leakage of air through tube 68.

It is preferable that subatmospheric pressures exist within the tube 63 prior to and at the time the thread is cut by the cutter 38, and for at least a short interval thereafter. This result may be accomplished either by using a continuous vacuum system, or one in which the system is subjected to subatmospheric pressures at the required time only when the lay is near its front center position.

On a later beat of the loom the thread will

5 be cut by temple cutter TC at the selvage of the cloth, resulting in complete removal of the thread. The upward and forward motion of the thread remover as suggested in Fig. 3 will draw the left hand part of the thread T to some such position as indicated in dotted lines c, Fig. 11, to place the thread in a favorable position for cutting by the temple cutter. Since the thread at this time extends from the intake mouth downwardly into tube 68 gravity will tend to hold the thread in the tube.

10 From the foregoing it will be seen that the invention sets forth a simple form of pneumatic thread remover for the thread of the outgoing bobbin which, when moving from its thread pick-up position back to normal position, moves the thread forwardly and upwardly in such manner that the plate 75 mechanically exerts a positive force lifting the thread to a position where it will fall by gravity along the notch 83 to the thread intake mouth 74. Also, the thread remover moves to its pick-up position as soon as the magazine is set for a replenishing operation with the notch 83 opening rearwardly toward the thread. 15 As soon as the advancing lay moves the thread within the zone of action of the partial vacuum at mouth 74 the cutter 38 operates and a loop or bend of thread is drawn into mouth 74 while the remover is still down. Thereafter 20 the magazine is reset and the remover swings upwardly and the thread extends downwardly from mouth 74 into tube 68. Furthermore, the plate 72, and more particularly its inclined edge 73, overlaps the under surface 19 of the shuttle 25 feeler as suggested in Fig. 10 so that as the thread is moved forwardly by the lay the shuttle feeler directs it into notch 83 toward the intake mouth. The tube 66 is flattened throughout the greater 30 part of its length and has a cross section more or less the same as that of the intake mouth, so that there is little turbulence within the tube and the thread can be acted upon to greater advantage by the stream of air moving through the tube. The flattened shape of tube 68 favors entry 35 of a relatively stiff thread into it without however requiring the tube to have a large internal air volume, thereby enabling a minimum of moving air to act properly on the thread.

40 Having thus described the invention it will be seen that changes and modifications of the foregoing specific disclosure may be made without departing from the spirit and scope of the invention.

45 What is claimed as new is:

50 1. In a weft replenishing loom having a thread to be removed extending from the cloth along a backwardly and forwardly reciprocating lay, a pneumatic thread remover having a thread intake mouth in front of the thread, and a shuttle 55 position detector over the lay and thread extending forwardly toward the remover and having a downwardly and forwardly inclined surface effective during forward motion of the lay to direct the thread toward said intake mouth.

60 2. In a weft replenishing loom having a thread to be removed extending from the cloth along the lay, a shuttle position detector extending in a generally horizontal direction over the thread, a pneumatic thread remover having an intake mouth in front of the thread, and downwardly 65 and forwardly extending thread guiding surfaces on the shuttle position detector and remover above the level of the intake mouth directing the thread downwardly toward said intake mouth during forward motion of the lay.

3. In a weft replenishing loom having a thread to be removed extending from the cloth along a backwardly and forwardly reciprocating lay, a shuttle position detector supported at a point rearward of the lay when the latter is in the forward position thereof and extending forwardly and having a thread guiding surface over the thread, and a pneumatic thread remover having a thread intake mouth in front of the thread and a guide surface extending downwardly and forwardly above the level of and toward the mouth, the thread if above said mouth being directed during forward motion of the lay by said surface on the detector and said surface on the remover toward said intake mouth.

4. In a weft replenishing loom having a thread to be removed extending from the cloth along a backwardly and forwardly reciprocating lay, a shuttle position detector extending in a generally horizontal direction above the lay and thread and normally in raised position and having a forwardly and downwardly extending thread guide surface, said detector moving downwardly to a detecting position on weft replenishing beats of the loom, and a pneumatic thread remover having a thread intake mouth in front of the thread on weft replenishing beats of the loom and provided with a guide surface which extends downwardly and forwardly to said mouth, said guide surfaces on the detector and remover co-operating when the detector is in detecting position during forward motion of the lay to direct the thread toward said intake mouth.

5. In a weft replenishing loom having a thread to be removed extending from the cloth along a backwardly and forwardly reciprocating lay, a pneumatic thread remover having a thread intake mouth in front of the thread and formed with a thread notch opening rearwardly from said mouth, and a shuttle position detector extending over the thread and having a thread guide surface effective to direct the thread into said notch during forward movement of the lay.

6. In a weft replenishing loom having a thread to be removed extending along a backwardly and forwardly reciprocating lay, a pneumatic thread remover having a thread intake mouth in front of the thread and having a thread engaging member extending rearwardly from said mouth below the thread and having also a thread guide surface extending upwardly and rearwardly from said mouth, said member and guide surface defining a rearwardly opening notch extending rearwardly from said mouth, and a shuttle position detector having a thread guiding surface over the thread effective during forward movement of the lay to direct said thread to a position between said member and said thread guide surface of the remover into said notch and toward said mouth.

7. In a weft replenishing loom having a thread to be removed extending along a backwardly and forwardly reciprocating lay provided with a race plate over which the thread extends, a pneumatic thread remover having a thread intake mouth in front of the thread and having a part below said shuttle race and another part above said race, said parts extending rearwardly from the intake mouth, and a shuttle position detector extending transversely of the lay over the race plate and having a thread guiding surface effective during forward movement of the lay to direct the thread to a position between said parts of the remover and toward said mouth.

8. In a weft replenishing loom having a thread

to be removed extending along the lay, a pneumatic thread remover having an intake mouth and having parts thereof extending away from said mouth to define a thread notch, a pivotal support for said remover forward of the lay, and operating means for the remover effective to position said remover with the notch opening rearwardly to receive the thread as the lay moves forwardly and thereafter moving the remover around said pivotal support to a position in which said notch opens upwardly and the thread tends due to gravity to fall toward said intake mouth.

9. In a weft replenishing loom having a thread to be removed extending along a lay, a pivotal support forward of the lay, a part of the loom moving first in one direction and then in the opposite direction incident to a weft replenishing operation of the loom, and a pneumatic thread remover movable angularly on said pivotal support and operatively connected to said part, said remover having a thread intake mouth and thread guiding means defining a thread notch leading to said mouth, said part of the loom when moving first in said one direction moving said remover to a position enabling the thread due to forward movement of the lay to enter said notch and said part of the loom when moving in the opposite direction moving said remover to a position in which the guide means thereof extends upwardly from said mouth and the thread due to gravity tends to fall toward said mouth.

10. In a weft replenishing loom having a thread to be removed extending along a backwardly and forwardly reciprocating lay, a pneumatic thread remover having an intake mouth and means defining a thread receiving notch leading to said mouth, means mounting said remover for pivotal motion backwardly and forwardly with respect to the lay, and means operative incident to a weft replenishing operation of the loom to move said remover on said mounting means toward the lay with said notch opening rearwardly to receive the thread as the lay moves forwardly and thereafter turn the remover or said mounting means away from the lay to a position in which said notch opens upwardly and the thread tends by gravity to fall toward said mouth.

11. In a weft replenishing loom having a thread to be removed extending along a backwardly and forwardly reciprocating lay, a pneumatic thread remover having means defining a thread notch leading toward a thread intake mouth, means mounting the remover for movement to one position in which the notch opens rearwardly and to another position in which the notch opens upwardly, and means operated by the loom positioning said remover in said one position with the notch opening rearwardly to receive the thread during forward motion of the lay and thereafter moving the remover to said other position in which said notch opens upwardly from said mouth so that a thread in the notch tends to fall by gravity toward said intake mouth.

12. In a weft replenishing loom having a thread to be removed extending along a backwardly and forwardly reciprocating lay, a pneumatic thread remover having a thread intake mouth and means defining a thread guiding notch leading to said mouth, means mounting the remover for motion either to thread pick-up position in which the notch opens rearwardly or to non-pick-up position in which the notch opens upwardly, and means operatively connected to the remover effective incident to a weft replenishing operation of the loom to move the remover to the

11

pick-up position thereof to receive the thread during forward motion of the lay and thereafter move said remover to the non-pick-up position thereof during continued forward motion of the lay to enable the thread by gravity to fall toward said mouth.

13. In a weft replenishing loom having a thread to be removed extending along a backwardly and forwardly reciprocating lay, a pneumatic thread remover having an intake mouth and having a part extending rearwardly from the mouth under the thread as the lay moves forwardly, a pivotal support for the remover, and means operating incident to a weft replenishing operation of the loom moving said remover around said pivotal support in a direction to move said part thereof upwardly and forwardly to lift the thread to a position in which the latter tends by gravity to fall toward the intake mouth.

14. In a weft replenishing loom having a thread to be removed extending along a backwardly and forwardly reciprocating lay, a pneumatic thread remover having an intake mouth and a plate extending rearwardly from and below said mouth under the thread as the lay moves forwardly, a pivotal support for said remover forward of the lay, and means operating incident to a weft replenishing operation of the loom moving said remover angularly around said support in a direction to move said plate upwardly and forwardly to a position beyond and behind said mouth and in which the thread will tend by gravity to fall along said plate toward said mouth.

15. In a weft replenishing loom having a thread to be removed extending along a lay, a pneumatic thread remover including a tube in which subatmospheric pressures exist for the purpose of removing a thread, said tube having a thread receiving mouth of elongated form the greater dimension of which extends lengthwise of the thread and the tube throughout a substantial part of the length thereof leading from said mouth transversely of the thread and having a cross section substantially the same as that of the mouth.

16. In a weft replenishing loom having a thread to be removed extending along a lay, a pneumatic thread remover including a tube flattened on the top and bottom sides thereof extending transversely of the thread and having a thread intake mouth of greater length measured in the direction of the thread than height measured transversely of the thread, said tube having substantially the same internal cross sectional shape as the mouth throughout a substantial part of the length thereof extending from the mouth.

17. In a weft replenishing loom having a thread to be removed extending along a lay, a pneumatic thread remover including a carrier and a tube on the carrier having a thread intake mouth at the end thereof remote from said carrier, said mouth being elongated in the direction in which the thread extends along the lay, the tube extending transversely of the thread away from said mouth and having substantially the same elongated cross sectional shape as the mouth throughout the greater part of the length thereof from the mouth to said carrier, and means pneumatically connected to the part of the tube remote from said mouth creating subatmospheric pressures within the tube.

18. In a weft replenishing loom having a thread to be removed extending from the cloth along a reciprocating lay to the eye of a shuttle on the lay, a pivotal support in front of the lay, a pneumatic thread remover pivoted on said sup-

port normally in raised non-pick-up position but movable downwardly to thread pick-up position, a weft replenishing mechanism including a preventer shaft having a movement from the normal position thereof to a setting position preparatory to bobbin transfer and then returning to normal position as the lay approaches front center, operative connections between the shaft and the remover causing the latter to move to the pick-up position thereof when said shaft moves to the setting position thereof, the advancing lay moving the thread toward the remover in pick-up position, and means cutting the thread adjacent to the eye of the shuttle after the remover has moved to the pick-up position thereof, said operative connections causing the remover to return to the non-pick-up position thereof as said shaft returns from the setting position to the normal position thereof.

19. In a weft replenishing loom having a thread to be removed extending from the cloth along the lay, weft replenishing mechanism including a preventer shaft rocking from the normal position thereof to a setting position to set the mechanism for a bobbin transfer and thereafter returning to normal position, pivotal support means in front of the lay, a pneumatic thread remover having a thread intake mouth and mounted on the support and rotatable thereon to be in either thread pick-up or in non-pick-up position, and operating connections between the shaft and the remover including a yieldable resilient member, said shaft when moving to the setting position thereof acting through said operative connections to move the thread remover about said pivotal mounting to thread pick-up position with said mouth in front of the thread, said shaft when returning to the normal position thereof acting through said resilient member to exert a force on said remover tending to move the latter to non-pick-up position, said resilient member yielding in the event that the shuttle is misplaced and engages the remover to prevent movement thereof from the pick-up to the non-pick-up position thereof when the lay is near the front center position, the lay subsequently moving away from front center position out of engagement with the remover, whereupon said resilient member moves the thread remover to non-pick-up position.

20. In a weft replenishing loom having a thread to be removed extending from the cloth along the lay, a pneumatic thread remover pivotally mounted in front of the lay and normally in non-pick-up position but movable to thread pick-up position, weft replenishing mechanism including a preventer shaft movable from the normal position thereof to the setting position thereof preparatory to a weft replenishing operation of the loom when the lay is in the rearward part of the stroke thereof and returning to the normal position thereof as the lay approaches the front center position thereof, and a connector operatively connecting said shaft and remover capable of exerting a positive force moving the remover from the non-pick-up position to the pick-up position thereof in front of the thread when the shaft moves to the setting position thereof, said connector including a spring transmitting force from the shaft to said remover when the shaft returns to the normal position thereof tending to move the remover back to the non-pick-up position thereof, said spring yielding in the event that a misplaced shuttle due to engagement with the remover prevents movement of the latter to

the non-pick-up position thereof when the lay is on front center but effecting return of the remover to the non-pick-up position thereof when the lay due to rearward movement thereof moves the shuttle out of engagement with the remover.

21. In a weft replenishing loom having a thread to be removed extending from the cloth along the lay to a shuttle, a pneumatic thread remover normally in non-pick-up position but moving to thread pick-up position incident to a weft replenishing operation, the remover having a thread intake mouth and a thread lifting member extending upwardly from the mouth when the remover is in non-pick-up position and rearwardly from the mouth under the thread when the remover is in pick-up position, and means moving the remover from the pick-up to the non-pick-up position thereof when a weft replenishing operation is prevented, the member lifting the thread as the remover returns to non-pick-up position, said member being formed with a thread clearing edge extending in a direction lengthwise of the lay upwardly and toward the cloth over which the thread slides when the shuttle is picked.

22. In a weft replenishing loom having a thread to be removed extending from the cloth along the lay, a pneumatic thread remover pivotally mounted forwardly of the lay including a tube

and a thread intake mouth at the end of the tube, said remover being capable of assuming a thread pick-up position in which the tube is substantially horizontal and the intake mouth is forward of the thread to receive the latter as the lay moves forwardly or capable of assuming a non-pick-up position in which the tube extends upwardly with the intake mouth at the upper end thereof so that a thread in the mouth extending into the tube is held in the latter by gravity, and means operated by the loom incident to a weft replenishing operation moving the remover first to the thread pick-up position thereof and thereafter moving the remover to the non-pick-up position.
